FOLIAGE UNIT FOR A MINIATURE
PORTABLE CHRISTMAS TREE

Nicholas T. Baldanza, Rutherford, N. J., assignor
to Columbia Protektosite Co., Inc., Carlstadt,
N. J., a corporation of New Jersey

Application June 30, 1950, Serial No. 10,884

Term of patent 7 years

(Cl. D29—1)

To all whom it may concern:

Be it known that I, Nicholas T. Baldanza, a citizen of the United States and resident of Rutherford, in the county of Bergen, State of New Jersey, have invented a new, original, and ornamental Design for a Foliage Unit for a Miniature Portable Christmas Tree, of which the following is a specification, reference being had to the accompanying drawing, forming a part thereof, and of which

Fig. 1 is a top plan view of a foliage unit for a miniature portable Christmas tree, showing my new design.

Fig. 2 is a sectional view taken on line 2—2 in Fig. 1.

Fig. 3 is an enlarged fragmentary sectional view taken on line 3—3 in Fig. 1, and

Fig. 4 is an enlarged fragmentary plan view as seen from line 4—4 in Fig. 3.

I claim:

The ornamental design for a foliage unit for a miniature portable Christmas tree, as shown.

NICHOLAS T. BALDANZA.
